UNITED STATES PATENT OFFICE.

HERMAN R. FRENSDORF, OF KIMBERLY, WISCONSIN.

GUN-SIGHT.

1,307,441.

Specification of Letters Patent. Patented June 24, 1919.

Application filed October 19, 1918. Serial No. 253,692.

To all whom it may concern:

Be it known that I, HERMAN R. FRENSDORF, a citizen of the United States, and resident of Kimberly, in the county of Outagamie and State of Wisconsin, have invented new and useful Improvements in Gun-Sights, of which the following is a description, reference being had to the accompanying drawings, which are a part of this specification.

The invention relates to gun sights and is fully described and explained in the following specification and shown in the accompanying drawings in which:

Figure 1 is a view of a gun barrel provided with sights embodying the invention, parts being shown in section and parts being broken away; Fig. 2 is a rear view of the rear sight; Fig. 3 is a plan view of the rear sighting member; Fig. 4 is a detail view of the rear sight, parts being broken away; Fig. 5 is a section taken on the line 5—5 of Fig. 1; Fig. 6 is a plan view of the front sight; Fig. 7 is a rear view of the front sight; Fig. 8 is a view of the sighting members in sighting position.

The rear sight consists of a base member 9 having sides 10 either formed with or joined to the part 11 which is attached to the gun barrel 12 and having a spring leaf portion 13 having its sides 14 spaced from the sides 10 and its outer end 15 spaced from the end portion 15'. The sides 10 have notches 16 cut or formed therein, receiving pins 17 which are secured to or formed integral with a frame 18 having side members 19 and 20, and a top plate 21 secured to the frame by screws 22.

These members 19 and 20 form guides for a sliding frame 23 which is slidably mounted at one side in an angular groove 24 in the member 19 and has an angular groove 25 in its other side, the sides of which groove engage the member 20 as shown in Fig. 5.

This frame 23 has a sighting member 26 inset in it as shown. The frame 23 has a lengthwise extending threaded bore 27 receiving a threaded rod 28 which is journaled at its lower end in the base of the frame 18 and carries a collar 29 and a knurled head 30 at its upper end, the plate 21 being interposed between the collar 29 and head 30, the rod passing through said plate. With this construction the turning of the rod 28 in the proper direction will raise or lower the frame 23 with respect to the frame 18 so that

the sighting member 26 may be set in the desired position.

A small lug 31 projects from the lower portion of the frame 18 and engages the spring leaf 13 adjacent the pivot and in this way the rear sight may be held in upright position as shown in full lines in Fig. 1, or it may be turned down into horizontal position as shown in dotted lines in Fig. 1. The frame 18 is secured to the base member before said member is attached to the barrel by slipping the pins 17 into the notches 16 while the spring 13 is pressed outwardly. The frame 18 also has a sighting member 32 secured to or formed integral with its lower end and projecting rearwardly therefrom and provided with the usual V-notch 33 so that when the rear sight is turned down against the barrel this member 32 is used for sighting at close or point blank range, the plate 21 having a notch 21' cut therein so as not to interfere with the use of the member 32. The sighting member 26 has an opening therein providing finding fields 27', a centrally disposed depending part 28' and a centrally disposed V-notch 29'. Contrary to usual practice the V-notch 29' is not used to determine the elevation but is used to center up the sight with the front sight while the pointed part 28' co-operates with the front sight to obtain the correct elevation without excluding the object aimed at.

The front sight consists of a base member 34 of usual construction and two leaves 35 and 36 secured to said base and having their abutting sides forming a center line 38. To more clearly mark off this center line the rear edges 39 and 40 of the leaves are beveled inwardly toward the center line 38 to form a V-notch 41 which however does not extend to the outer sides of the leaves but meets straight horizontal surfaces 42 which prevent blurring. Of course the leaves 35 and 36 might be made in one piece, but it is easier to make them separate and join them to the base.

The sights thus formed co-operate in the following manner: To obtain a line on the object, the object is brought within the fields 27 and the front sight is lined up with the rear sight by bringing line 38 into position to bisect the notch 41, that is the line 38 extends vertically from the apex of the notch 41. With the parts thus in line the proper elevation is obtained by bringing the point 28' down to a position where it touches a

line sighted across the surfaces 42, that is the tip 28', and surfaces 42 are brought into line with each other.

To provide for shooting at different ranges 5 the rear sighting member 26 is raised and lowered as previously described and provided with an indicating mark 43 in line with the tip of the point 28' and coöperating with a range scale 44 on the member 20. For 10 fine adjustment the plate 21 is provided with a scale 45 and the head with a pointer 46.

From the foregoing description it will be noted that when the sights are lined up there are sighting fields on both sides of the center 15 so that the object is plainly visible and that the sighting elements of the rear and front sights are themselves spaced apart when brought into proper position so that the object can be clearly seen, both of which features provide for quick and accurate sighting.

What I claim as my invention is:

1. The combination of a front sight having a V-notch and a rear sight having an 25 opening through which the front sight is visible and a depending pointer coöperating with said notch to determine the sighting elevation without excluding the object from view.

30 2. The combination of a front sight having a V-notch and a rear sight having an opening through which the front sight is visible and a depending pointer coöperating with said notch to determine the sighting 35 elevation by bringing the tip of said pointer into line with a line passing through the base of the notch whereby said sights are spaced from each other to give a clear view of the object.

40 3. The combination of a front sight having a V-notch and a rear sight having a downwardly projecting point coöperating with said notch to determine the sighting elevation, and coöperating means on said 45 sights for lining them up.

4. The combination of a front sight hav-

ing a V-notch and a center line bisecting the apex of said notch, and a rear sight having a V-notch coöperating with said center line for lining up said sights, and coöperating means 50 on said sights for determining the elevation.

5. The combination of a front sight having a V-notch and a center line bisecting the apex of said notch, and a rear sight having a V-notch and a depending projection centrally disposed and spaced from each other and finding fields, said center-line of the front sight coöperating with the V-notch of the rear sight to line up said sights in a horizontal plane and said V-notch of the 60 front sight coöperating with said projection to determine the elevation of sight.

6. The combination of a front sight and a rear sight, coöperating means on the sights for lining them up, and coöperating means 65 to determine the elevation of sight without excluding vision of the part of the object aimed at.

7. The combination of a front sight and a rear sight, coöperating means on the sights 70 for lining them up, and coöperating means on the sights to determine the elevation of sight without excluding vision of the part of the object aimed at, said rear sight also having finding fields on each side of the line 75 of sight to permit a view of the object aimed at.

8. A front sight provided with a center line and a V-shaped notch bisecting said center line at the rear portion of said sight, 80 one of the rear portions of the sight adjacent the center line extending beyond the other to clearly define said center line.

9. A front sight provided with a center line, a V-shaped notch bisecting said center 85 line at the rear portion of said sight and straight surfaces extending laterally from the base of said notch to prevent blurring.

In testimony whereof, I affix my signature.

HERMAN R. FRENSDORF.
